Attorney

UNITED STATES PATENT OFFICE.

JAY J. HOGAN, OF ERIE, PENNSYLVANIA.

WASHING MACHINE.

Application filed July 3, 1924. Serial No. 724,002.

To all whom it may concern:

Be it known that I, JAY J. HOGAN, a citizen of the United States, residing at Erie, in the county of Erie and State of Pennsylvania, have invented new and useful Improvements in Washing Machines, of which the following is a specification.

This invention is designed to improve washing machines of the beater type and is 10 along the lines of a structure described in an application now pending by me, Serial Number 668,545, filed Oct. 15th, 1923, in which a beater carrier is given an orbital movement creating an oscillatory movement 15 of beater cups. With the present invention the carrier is locked against rotary movement relatively to the tub and this is accomplished in a simple and efficient manner through a protected mounting. The invention 20 involves the sealing of the operating mechanism, a quick release for the beater and carrier, and a simplified arrangement of the driving mechanism. Other features and details of the invention will appear from 25 the specification and claims.

The invention is illustrated in the accompanying drawings as follows:—

Fig. 1 shows a central section through the tub.

Fig. 2 an enlarged section of the means for releasing the beater carrier from its mounting.

Fig. 3 an enlarged view of the top of the housing having a carrier mounting.

Fig. 4 a section on the line 4—4 in Fig. 3. 35 1 marks the tub. This has the side walls 2, bottom wall 3, and a central upright sleeve 4, this being ordinarily made of sheet metal. The hub rests on a frame having a 40 platform 5 and the frame is carried by legs 6. Secured to the main frame 5 is a driving casing 7. A housing 8 which really forms the mounting support for the carrier mounting is secured to the driving casing 7 and 45 extends upwardly within the central sleeve 4 of the sheet metal tub, the two being joined at the top.

Beater cups 9, preferably of the vacuum type, are secured to a carrier 10, there being a plurality of these cups, ordinarily five, secured to the carrier. The carrier is 50 mounted on a shaft 11. The shaft is secured in a clamp 12 in a gimbal joint 13 mounted in a housing 8. Thus the shaft is 55 free to wobble or have an orbital movement

at its ends but is locked against rotation. The lower end of the shaft is journaled in an opening 14 in a crank arm 15 on a vertical shaft 16 journaled in the driving casing 7. A cap 17 is arranged on the upper 60 end of the housing. It has a sleeve 18 fixed in it in which are bearing sleeves 19 in which the shaft 11 is journaled. Wheels 20 are journaled on pins 21 extending downwardly from the top, the wheels being held 65 in place by washers 22 locked on the pins by cotter pins 23. The wheels 20 are at opposite sides of a vertical plane extending through the shaft 11. Their only function is to maintain the cap 17 in axial alinement 70 with the housing.

The cap is sealed on the housing by a flexible flap 24 preferably of oiled leather or similar material and this is secured on a surface 25 at the underside of the cap by 75 a clamp 26 which is secured by screws 27. A coiled spring 28 extends entirely around the cap directly over the flap and is tensioned against a cam surface 29, the effect of which is to urge the coil springs downwardly on the flap and to yieldingly press the flap against a flange 30 on the upper end of the sleeve 4. Thus there is maintained a water tight joint at the upper end 80 of the housing with very little frictional resistance.

The carrier is detachably mounted on the upper end of the shaft by the following mechanism: A cap 31 is secured to the upper end of the shaft by a pin 32 and the 85 cap forms a housing over the bearing sleeve 19. The carrier has a thimble 33 secured in a head 34. This is secured by means of rivets 33^a having extensions 33^b which extend through openings 31^a in the cap 31, 90 thus locking the carrier against rotation. There are preferably a number of holes 31^a so that all that is necessary is to drop the carrier in place and give it a slight rotation to bring the ends 33^b into register with the 100 openings 31^a. The head 34 has a projection 35 on which a lever 36 is pivotally mounted by means of a pin 35^a. The lever is bifurcated, the arms extending each side of the cap 31. A latch 37 is pivotally mounted by means of a pin 38 between the arms of the bifurcated lever 36 and is adapted to be opened or forced outwardly by a conical surface 39 at the top of the cap and to swing under a shoulder 40 when the cap 110

drops to place, the arm 37 being spring-pressed by means of a spring 41 operating on a bell crank arm 42 of the latch 37. A projection 43 extends from the latch so that 5 it may be conveniently manipulated to release the carrier. In order to more firmly secure the carrier a screw 44 extends through the lever 36 and after the latch is engaged by setting down this screw the carrier 10 can be more firmly seated on the cap.

The washer is driven by an electric motor 45 suspended from the frame 5. A motor shaft 46 has a worm 47 engaging a worm gear 48. The worm gear 48 is fixed on a 15 shaft 49 journaled in the driving frame. A gear 50 is fixed on the shaft 49 and meshes with a gear 51 carried by a shaft 52. The shaft 52 is journaled in the driving frame. The gear 51 meshes with a gear 53 fixed on 20 the shaft 16. The gear 53 has clutch detents 54 adapted to operate with a sliding jaw clutch element 55 slidably mounted on the shaft 16 and locked against rotation thereon by a spline 55^a. The clutch element 25 has the usual groove 56 in which is arranged a collar 57. A forked lever 58 engages the collar and is mounted on a shaft 59. The shaft extends crosswise to the side of the machine and an operating lever 60 is 30 secured to the shaft. By throwing the operating lever the clutch may be thrown into and out of engagement so as to set the washer in motion.

A gear 61 meshes with the gear 50 and 35 this in turn meshes with a gear 62. The gear 62 drives a shaft 63 which may be utilized to drive a wringer (not shown).

It will be noted that the housing 8 is closed by the bottom 8^a and that the frame 7 40 entirely encloses and houses the gears. These are important features in a structure of this type in that the housing may be loaded with grease and the frame or housing for the gears loaded with grease sufficient 45 to handle the lubrication of the machine for an indefinite period extending at least into years.

What I claim as new is:—

1. In a washing machine, the combination 50 of a tub; a beater carrier within the tub; an orbital mounting for the carrier; beaters on the carrier elevated and depressed by the orbital movement of the carrier; a rotary driver imparting orbital movement to the carrier; devices preventing a rotation of the beater equal to the orbital movement; and means separating said devices from the interior of the tub.

2. In a washing machine, the combination 60 of a tub; a beater carrier within the tub; an orbital mounting for the carrier; beaters on the carrier elevated and depressed by the orbital movement of the carrier; a rotary driver imparting orbital movement to the carrier; devices locking the beater

against rotation relatively to the tub; and means separating said devices from the interior of the tub.

3. In a washing machine, the combination 70 of a tub; a beater carrier within the tub; an orbital mounting for the carrier comprising a gimbal joint; beaters on the carrier elevated and depressed by the orbital movement of the carrier; a rotary driver imparting orbital movement to the carrier; 75 and devices locking the carrier through the gimbal joint against rotation.

4. In a washing machine, the combination 80 of a tub; a beater carrier within the tub; an orbital mounting for the carrier comprising a gimbal joint; beaters on the carrier elevated and depressed by the orbital movement of the carrier; a rotary driver imparting orbital movement to the carrier; 85 devices locking the carrier through the gimbal joint against rotation; and means for separating said devices from the interior of the tub.

5. In a washing machine, the combination 90 of a tub; a beater carrier within the tub; an orbital mounting for the carrier; beaters on the carrier elevated and depressed by the orbital movement of the carrier; a housing for the mounting extending upwardly from the bottom of the tub; a rotary driver imparting orbital movement to the carrier through the mounting; and means within 95 and below the top of the housing preventing a rotation of the carrier equal to the orbital movement.

6. In a washing machine, the combination 100 of a tub; a beater carrier within the tub; an orbital mounting for the carrier; beaters on the carrier elevated and depressed by the orbital movement of the carrier; a housing for the mounting extending upwardly from the bottom of the tub; a rotary driver 105 imparting orbital movement to the carrier through the mounting; and means within and below the housing preventing a rotation of the carrier equal to the orbital movement.

7. In a washing machine, the combination 115 of a tub; a beater carrier within the tub; an orbital mounting for the carrier; beaters on the carrier elevated and depressed by the orbital movement of the carrier; a housing for the mounting extending upwardly from the bottom of the tub; a rotary driver 120 imparting orbital movement to the carrier through the mounting; and means within and below the housing at the center of oscillation of the carrier preventing a rotation of the carrier equal to the orbital movement.

8. In a washing machine, the combination 125 of a tub; a beater carrier within the tub; a shaft on which the carrier is mounted; a non-rotatable universal joint with which the shaft is locked; a driver giving the shaft orbital movement; and beaters on the car-

- rier elevated and depressed by the orbital movement of the carrier.
9. In a washing machine, the combination of a tub; a beater carrier within the tub; a shaft on which the carrier is mounted; a gimbal joint in which the shaft is locked; a driver giving the shaft orbital movement; and beaters on the carrier elevated and depressed by the orbital movement of the carrier.
10. In a washing machine, the combination of a tub; a beater carrier within the tub; a shaft on which the carrier is mounted; a gimbal joint having an element with which the shaft is clamped; a crank operating on the lower end of the shaft for giving the shaft orbital movement; and beaters on the carrier elevated and depressed by the orbital movement of the carrier.
11. In a washing machine, the combination of a tub; a beater carrier within the tub; a shaft on which the carrier is mounted; a housing extending upwardly from the bottom of the tub; a non-rotatable universal joint arranged in the housing with which the shaft is locked; a crank operating on the lower end of the shaft giving to the shaft orbital movement; and beaters on the carrier elevated and depressed by the orbital movement of the carrier.
12. In a washing machine, the combination of a tub; a beater carrier within the tub having beater cups rigidly mounted thereon; an orbital mounting for the carrier having its orbital center in a plane approximately the plane of the cups, said cups being elevated and depressed by the orbital movement of the carrier; and devices for preventing the rotation of the carrier equal to the orbital movement.
13. In a washing machine, the combination of a tub; a beater carrier within the tub having beater cups rigidly mounted thereon; an orbital mounting for the carrier having its orbital center in a plane approximating the plane of the cups, said cups being elevated and depressed by the orbital movement of the carrier; devices for preventing the rotation of the carrier equal to the orbital movement; and means separating said devices from the interior of the tub.
14. In a washing machine, the combination of a tub; a beater carrier within the tub; an orbital mounting for the beater carrier; beaters on the carrier elevated and depressed by the orbital movement of the carrier; a housing extending upwardly from the bottom of the tub for the mounting; a rotary cap sealing the top of the housing; and a yielding seal for the cap.
15. In a washing machine, the combination of a tub; a beater carrier within the tub; an orbital mounting for the beater carrier; beaters on the carrier elevated and depressed by the orbital movement of the car-
- rier; a housing extending upwardly from the bottom of the tub for the mounting; a rotary cap sealing the top of the housing; and a yielding seal for the cap comprising a flexible flap.
16. In a washing machine, the combination of a tub; a beater carrier within the tub; an orbital mounting for the beater carrier; beaters on the carrier elevated and depressed by the orbital movement of the carrier; a housing extending upwardly from the bottom of the tub for the mounting; a rotary cap sealing the top of the housing; and a yielding seal for the cap comprising a flexible flap and an annular spring operating on the flap.
17. In a washing machine, the combination of a tub; a beater carrier within the tub; an orbital mounting for the beater carrier; beaters on the carrier elevated and depressed by the orbital movement of the carrier; a housing extending upwardly from the bottom of the tub for the mounting; a rotary cap sealing the top of the housing; and a yielding seal for the cap comprising a flexible flap, an annular spring operating on the flap, and a cam on the cap on which the spring seats deflecting the spring toward the flap.
18. In a washing machine, the combination of a tub; a beater carrier in the tub; an orbital mounting for the beater carrier; beaters on the carrier elevated and depressed by the orbital movement of the carrier; an upwardly extending housing in which the mounting is arranged; a cap journaled on the mounting; and means maintaining the cap in central alinement with the housing.
19. In a washing machine, the combination of a tub; a beater carrier in the tub; a shaft on which the carrier is mounted; a housing extending upwardly from the bottom of the tub; an orbital mounting for the shaft within the housing; a crank engaging the lower end of the shaft to give it orbital movement; beaters on the carrier elevated and depressed by the orbital movement of the carrier; a cap for the housing journaled on the shaft; and means on the cap maintaining it in central position relatively to the housing.
20. In a washing machine, the combination of an orbital shaft; a beater carrier removably mounted on the shaft; a latch locking the carrier on the shaft; and a screw clamping the latch.
21. In a washing machine, the combination of a beater carrier; an orbital shaft on which the carrier is removably mounted, said carrier having a cap with a shoulder thereon; a lever mounted on the carrier extending past the cap; and a latch journaled on the lever and adapted to engage the shoulder on the cap.
22. In a washing machine, the combina-

tion of a beater carrier; an orbital shaft on which the carrier is removably mounted, said carrier having a cap with a shoulder thereon; a lever mounted on the carrier extending past the cap; a latch journaled on the lever and adapted to engage the shoulder on the cap; and a screw for clamping the latch on the shoulder.

23. In a washing machine, the combination of a beater carrier; an orbital shaft on which the carrier is removably mounted, said carrier having a cap with a shoulder thereon; a lever mounted on the carrier extending past the cap; a latch journaled on the lever and adapted to engage the shoulder on the cap; and a conical end on the cap for opening the latch.

24. In a washing machine, the combination of a tub; a main frame on which the tub is mounted; a driving frame on the main frame; a housing carried by the driving frame and extending upwardly into the tub; a beater carrier in the tub; an orbital mounting in the housing for the carrier; beaters on the carrier elevated and depressed by the movement of the carrier; and means acting

through the driving frame for driving the carrier through the mounting.

25. In a washing machine, the combination of a tub having sides, a bottom, and an upwardly extending sleeve; a main frame on which the tub is mounted; a driving frame mounted on the main frame; a housing extending upwardly from the driving frame within the sleeve; a beater carrier; an orbital mounting for the carrier in the housing; beaters on the carrier elevated and depressed by the movement of the carrier; and means in the driving frame for driving the carrier.

26. In a washing machine, the combination of a tub; an upwardly extending housing in the tub; a beater carrier within the tub; an orbital mounting for the beater extending into the housing, said housing being grease tight and capable of carrying a lubricant for the mounting and beaters on the carrier elevated and depressed by the orbital movement of the carrier.

In testimony whereof I have hereunto set my hand.

JAY J. HOGAN.
